UNITED STATES PATENT OFFICE.

HARRY H. REX, OF YAKIMA, WASHINGTON, ASSIGNOR OF ONE-THIRD TO ANDREW SLAVIN AND ONE-THIRD TO FRANCIS R. SLAVIN, BOTH OF YAKIMA, WASHINGTON.

ROTARY PUMP.

Application filed June 23, 1926. Serial No. 117,988.

This invention relates to an improved rotary pump, and seeks, among other objects, to provide a device of this character, particularly applicable for service in any instance where high pressure is required, while, at the same time, the pump will also be well suited for general use.

The invention seeks, as a further object, to provide a pump which, while being particularly designed for pumping liquids, may also be employed for compressing air.

A still further object of the invention is to provide a pump which, when in operation, will deliver a practically continuous stream.

And the invention seeks, as a still further object, to provide a pump which will be sturdy in its construction, which may be readily taken apart or assembled, and which will be composed of a minimum number of parts consistent with entire efficiency.

Other objects of the invention not specifically mentioned in the foregoing will appear during the course of the following description.

In the accompany drawings:

Figure 1 is a side elevation of my improved pump.

Figure 2 is a transverse vertical sectional view through the device.

Figure 3 is a sectional view on the line 3-3 of Figure 2, looking in the direction indicated by the arrows.

Figure 4 is a sectional view on the line 4-4 of Figure 3, looking in the direction indicated by the arrows.

Figure 5 is a detail sectional view showing a slightly modified form of piston head.

In carrying the invention into effect, I employ a cylindrical center block or stator 10, and formed in the block are radial cylinders 11, the block being cored out between the cylinders as indicated at 12. In the present instance, I have shown the block as provided with four cylinders but, of course,

45 the number of cylinders employed may be varied as desired. Formed in the block to communicate with the inner ends of the cylinders are inlet passages 13 opening through one side of the block centrally thereof, and 50 leading from the inner ends of the cylinders are discharge passages 14 opening through the other side of the block centrally thereof, it being observed that the outer end portions

of all of said passages are tilted toward the axis of the block.

At suitably spaced points about the periphery thereof the block 10 is, as particularly seen in Figures 3 and 4, provided with transverse sockets 15 in which are mounted rollers 16, and rotatably supported by said rollers to freely turn about the block is the rotor employed. This rotor comprises a shell which is formed of mating side plates 17, and extending transversely through the plates at the outer peripheral margins thereof are spaced bolts 18 securing the plates together. At their inner peripheries, the plates are provided with lateral flanges 19 to coact with the rollers 16 and more or less closely surround the block 10, while, at their outer peripheries, the plates are formed with mating portions of a circumferential gear 20 extending around the rotor. In use, a suitable drive pinion, such as conventionally illustrated at 21, is arranged to coact with said gear for driving the rotor.

As particularly seen in Figures 3 and 4, the side plates 17 are cut away to define an internal annular chamber 22 concentric to the axis of the block 10, and fitting the periphery of said block are companion guide members 23 formed at their ends to define pairs of radial guides 24 fitting in said chamber. Securing the guide members to the block are cap bolts or other suitable fastening devices 25 so that, as will be seen, the guide members will thus serve to lock the rotor against lateral displacement from the block and, as will be observed, the guide members are of a length to extend between the cylinders 11 so that the pairs of guide members 24 are thus located at opposite sides of said cylinders respectively. Formed in the side plates 17 of the rotor shell are oppositely disposed internal grooves 26 which are eccentrically located with respect to the axis of the block.

Mounted to reciprocate in the cylinders 11 are the pump pistons. These pistons include piston rods 27 provided at their outer ends with T-shaped heads 28 which slidably fit between the pairs of guides 24, and extending transversely through said heads, as seen in Figure 2, are pins 29 upon the ends of which are journaled rollers 30 more or less snugly accommodated in the eccentric

grooves 26, the pins being fixed to the heads. Overlying the inner ends of the piston rods are washers 31 and abutting said washers are resilient piston heads 32 detachably secured to the rods by cap bolts 33 extending through said washers. At their inner ends, the piston heads are formed with annular V-shaped grooves 34 defining peripheral lips 35 which yieldably bear against the cylinder walls and, as will be seen, as each piston makes its inward stroke, fluid will enter the groove of the piston head for pressing the lip thereof radially outward in tight contact with the cylinder wall.

In Figure 5, I have illustrated a slightly modified form of piston head 36 which, if found advantageous, may be used in lieu of the heads 32. The piston head 36 is formed of suitable resilient material and is provided at its inner end with a conical cavity 37 defining a lip 38 at the periphery of the head. Thus, as will be seen, when the piston head 36 makes its inward stroke, fluid will enter the cavity 37 for expanding the lip 38 against the cylinder wall.

Resting in suitable seats at the outer ends of the intake passages 13 are valve cages 39 in which are mounted spring closed intake valves 40, and resting in suitable seats at the outer ends of the outlet passages 14 are cages 41 in which are mounted spring closed discharge valves 42, the cages being equipped with reversible valve seats 43 for said valves. Overlying the cages 39 is an intake manifold 44, and overlying the cages 41 is a discharge manifold 45. These manifolds are provided with flat inner end walls 46 in which are provided seats for the outer ends of the valve cages, and formed through said walls to communicate with the ports at the outer ends of the cages are openings 47. As seen in Figure 1, the manifolds 44 and 45 are provided with peripheral flanges 48, and extending freely through said flanges 45 are cap bolts 49 screwed at their inner ends into annular flanges 50 on the center block 10. Thus, the valve cages are rigidly clamped between the manifolds and the center block and, if found necessary, suitable gaskets may be employed to provide sealed joints between the valve cages and the manifolds as well as between the valve cages and the center block. At their outer ends, the manifolds are contracted to form nipples 51, and screwed into the nipple of the manifold 44 is an intake pipe 52 while a similar discharge pipe 53 is screwed into the nipple of the manifold 45. Any approved struc-

ture may be provided for mounting the block 10 and rigidly securing the block stationary.

As will now be seen, when the rotor is turned, the rollers 30 of the pistons will travel in the eccentric grooves 26 for reciprocating the pistons while the guides 24 will coact with the heads 28 of the piston rods for directing the pistons in their radial movement. The pistons will thus be limited to rectilinear travel and, as the pistons move outwardly within the cylinders 11, fluid will be drawn into the cylinders through the intake manifold 44, valve cages 39, and passages 13, while, as the pistons move inwardly within the cylinders, the fluid will be forced out through the passages 14, valve cages 41, and discharge manifold 45. If desired, the block 10 may be formed of aluminum and steel lining sleeves used in the cylinders 11, while, for pumping acids, porcelain sleeves may be employed in said cylinders.

Having thus described the invention, what I claim is:

1. A rotary pump including a center block having cylinders and provided with intake and discharge passages communicating with said cylinders, intake and discharge valves associated with said passages, pistons reciprocable in said cylinders, guide members carried by the block to coact with the pistons for limiting the pistons to rectilinear travel, companion side plates mating to form a rotor surrounding the center block and rotatable thereon, said side plates defining an internal cavity accommodating said guide members, and means carried by the rotor to coact with the pistons for reciprocating the pistons as the rotor is turned.

2. A rotary pump including a center block having radial cylinders and provided with intake and discharge passages communicating with said cylinders, intake and discharge valves associated with said passages, pistons reciprocable in said cylinders, guide members fixed to the periphery of the block to coact with the pistons for limiting the pistons to rectilinear travel, mating side plates forming a rotor surrounding the block and rotatable thereon, said side plates being formed with eccentric grooves and defining an internal annular chamber accommodating said guide members, pins carried by the pistons, and rollers journaled on said pins to travel in said grooves for reciprocating the pistons as the rotor is turned.

HARRY H. REX.
